UNITED STATES PATENT OFFICE.

JOHN A. KEPHART, OF WELLSTON, OKLAHOMA.

INSULATOR ATTACHMENT.

1,105,521.

Specification of Letters Patent.

Patented July 28, 1914.

Application filed August 15, 1913. Serial No. 784,994.

To all whom it may concern:

Be it known that I, JOHN A. KEPHART, a citizen of the United States, residing at Wellston, in the county of Lincoln and 5 State of Oklahoma, have invented new and useful Improvements in Insulator Attachments, of which the following is a specification.

This invention relates to improvements in 10 attachments for insulators and has particular application to a wire holding device.

In carrying out the present invention, it 15 is my purpose to provide a device of the class described which may be readily applied to an insulator on the cross arm of a pole or the like and which will receive and effectively grip the line wires or conductors and eliminate the necessity of wrapping or winding such conductors about the insulator. 20

It is also my purpose to provide a device of the type set forth which will embrace the desired features of simplicity, efficiency and durability coupled with cheapness of cost 25 in manufacture and marketing and which may be readily applied to and removed from the insulator.

With the above and other objects in view, the invention consists in the construction, 30 combination and arrangement of parts hereinafter set forth in and falling within the scope of the claims.

In the accompanying drawing, Figure 1 is a view in elevation of an insulator 35 equipped with a wire holding device constructed in accordance with the present invention, and Fig. 2 is a detail perspective view of the device removed from the insulator.

40 Referring now to the accompanying drawing in detail, the numeral 1 designates a glass insulator of the well known type having the usual grooves 2, 3 formed therein and spaced apart. This insulator as is well known is adapted to be threaded onto the pins carried by cross arms on the wire supporting poles so as to support the line wires or conductors.

45 My attachment comprises a split metallic

band 4 disposed within the groove 3 in the 50 insulator and having the extremities thereof outturned as at 5 and suitably clamped together through the medium of a rivet 6. Passed through the outturned portions adjacent to the rivet 6 is a pivot pin 7 upon 55 which is mounted one end of a lever 8, such lever adjacent to the pivot pin being formed with a laterally projecting heel 9 coöperating with notches 10, 10 formed in the upper edges of the outturned ends 5 of the band 60 4 to receive the line wires or conductors. The outer edge of this lever is preferably notched as at 11 to receive a loop 12 mounted within the eyes 13 formed in the outturned ends 14 of a strip 15 disposed within the groove 2. 65

From the foregoing description taken in connection with the accompanying drawing, the construction and manner of employing my invention will be readily apparent. When it is desired to secure a line wire to 70 the insulator, the loop 12 is swung out of engagement with the lever 8 and the latter moved about the pivot pin 7 so that the heel 9 moves away from the notches 10, 10. The line wires are now disposed within the 75 notches and the lever swung upwardly whereby the heel engages the line wires and coöperates with the notches to hold such wires in position, the loop being swung over the free end of the lever and engaged in one 80 or another of the notches 11.

It will be observed that I have provided an attaching device for insulators whereby line wires may be secured thereto without necessitating the wrapping of the wires 85 about the insulators as usual.

I claim:

1. The combination with an insulator, of a wire holding device comprising a split band surrounding said insulator and having 90 the ends thereof outturned and formed with notches in the upper edges thereof, a lever pivoted between its ends and formed with a heel coöperating with said notches to hold a wire in position, and means carried by 95 said insulator for locking said lever against movement.

2. The combination with an insulator, of

a wire holding device comprising a split band surrounding said insulator and having the ends thereof outturned and formed with notches in the upper edges thereof, a lever pivoted between its ends and formed with a heel coöoperating with said notches to hold a wire in position, a second band surrounding said insulator, and a loop carried by said

second band and designed to engage said lever to hold the latter against movement. 10

In testimony whereof I affix my signature in presence of two witnesses.

JOHN A. KEPHART.
